UNITED STATES PATENT OFFICE.

ALFRED P. FOSTER, OF ORANGE, NEW JERSEY, AND RALPH W. FOSTER, OF BOSTON, MASSACHUSETTS, ASSIGNEES TO WESTINGHOUSE ELECTRIC & MANUFACTURING COMPANY, A CORPORATION OF PENNSYLVANIA.

DEVICE FOR STARTING INTERNAL-COMBUSTION ENGINES.

1,185,300.

Specification of Letters Patent.

Patented May 30, 1916.

Application filed February 23, 1910. Serial No. 545,463.

To all whom it may concern:

Be it known that we, ALFRED P. FOSTER and RALPH W. FOSTER, citizens of the United States, and residents of Orange, in 5 the county of Essex and State of New Jersey, and of Boston, in the county of Suffolk and State of Massachusetts, respectively, have invented certain new and useful Improvements in Devices for Starting Internal-Combustion Engines, of which the following is a specification.

This invention relates to devices for starting internal combustion engines, more particularly such engines as are used on automobiles, aeroplanes and launches, and consists of gearing attached to the periphery of the fly wheel of the engine, an electric motor propelling a driver adapted to actuate the gearing, and means for releasing the 20 driver, as will be described in the specification, set forth in the claims and illustrated in the drawing, in which—

Figure 1 is an elevation of the device with the operating gearing in mesh, Fig. 2 is an 25 elevation of the device with the operating gearing out of mesh, Fig. 3 is a detail showing a releasing device, Fig. 4 is a section showing a slidable shaft on a polygonal motor shaft.

Referring to the drawing there is shown a fly wheel 11 having gearing 18 applied to its rim. The gearing 18 is actuated by gearing 19 on a driver 12. On a base 14 there rests a small electric motor M, connected by 35 the conductors 28 and 29 with a suitable source of electricity, the current being closed or opened by means of a push button not shown. To engage or disengage the gearing a screw cap 15 is turned by means of the 40 milled head 16. The screw cap 15 is pre-

vented from moving longitudinally by means of the collar 34 at the end of the arm 30. As the screw cap 15 revolves it actuates the screw 21 and moves the shaft 20 toward or away from the motor M thereby causing 45 the gear wheel 19 to engage with the gearing 18 or to become disengaged. The shaft 20 as it moves slides on the square shaft 32.

The driver may be very small compared with the fly wheel so that only a very small 50 force will be needed to move it.

In case of a "back-kick" the push button is released whereby the current is broken and no harm is done to the motor.

What we claim is:

1. In a device for starting internal combustion engines, the combination of a fly wheel provided with gear teeth, an electric motor provided with a shaft, a shaft slidably attached to the shaft of the motor, a 60 driver mounted on the slidable shaft and adapted to mesh with the fly wheel gear teeth, and means for moving the driver into and out of mesh with the fly wheel teeth.

2. In a device for starting internal combustion engines, the combination of a fly 65 wheel, provided with gear teeth, an electric motor provided with a polygonal shaft, a slidable shaft attached to the motor shaft, a driver on the slidable shaft adapted to 70 mesh with the fly wheel gear teeth, and means for disengaging the gear teeth.

Signed at New York in the county of New York and State of New York this 18th day of Feb. A. D. 1910.

ALFRED P. FOSTER.
RALPH W. FOSTER.
